UNITED STATES PATENT OFFICE.

THOMAS B. SOMERS, OF INDEPENDENCE, KANSAS.

PIPE-WRENCH.

1,103,323.

Specification of Letters Patent. Patented July 14, 1914.

Application filed September 10, 1912. Serial No. 719,617.

To all whom it may concern:

Be it known that I, THOMAS B. SOMERS, a citizen of the United States, residing at Independence, in the county of Montgomery, State of Kansas, have invented certain new and useful Improvements in Pipe-Wrenches; and I do hereby declare the following to be a full, clear, and exact description of the invention, such as will enable others skilled in the art to which it appertains to make and use the same.

This invention relates to wrenches and more particularly to pipe wrenches.

An object of the invention is to provide a wrench having a stationary jaw and a movable jaw with its shank movably secured in a rocking bracket and coöperating with said bracket and the shank by which the stationary jaw is carried.

Another object is to provide a wrench of this character which may be readily adjusted and the bracket of which will be resiliently retained in proper position to secure the movable jaw in adjusted position.

Another object is to generally improve and simplify the construction and operation of devices of this character and increase the efficiency and durability thereof.

With these and other objects in view, my invention will be more fully described and illustrated in the accompanying drawings attached to and forming a part of this application.

In the drawings: Figure 1 is a side elevation of my improved wrench. Fig. 2 is a longitudinal section therethrough. Fig. 3 is a cross sectional view on the line 3—3 Fig. 1. Fig. 4 is a view similar to Fig. 1 showing the manner of adjusting the movable jaw. Fig. 5 is a longitudinal section therethrough. Fig. 6 is a detail view of the rocking bracket removed.

Referring more particularly to the above drawings in which similar reference characters designate corresponding parts throughout, 10 designates the shank or handle, upon the forward end of which is carried the rigid or stationary jaw 11 and which has the rearwardly directed teeth 12 upon its outer edge, 50 at the forward end of said shank, it being understood that said forward end is wider than the remainder of the shank.

The movable jaw 13 has the shank portion 14 with the forwardly directed teeth 15 55 upon its inner edge for coöperation with the

teeth 12, as will be clearly seen. The shank portion 14 of the movable jaw 13 is adapted for longitudinal movement through and rocking movement in the main portion of the rocking sleeve 16, which sleeve is provided with the depending ears 17 on its opposite sides, through which ears 17 and the forward portion of the handle or shank 10 is positioned the pivot pin 18 upon which the sleeve 16 rocks. The rear portion of the bracket 16 is reduced and extended toward the rear end of the handle or shank 10, as shown at 19 upon opposite sides of said shank. The extended portions 19 are connected by means of the transverse wall 20 at the free ends of said extended portions and the pin 21 depends from the rear end of said wall and has the rear end of the curved leaf spring 22 secured thereto while the forward end of the spring presses against the outer edge of the shank 10 to yieldingly hold the wall 20 spaced from said edge of the shank 10.

It will be understood that both ends of the main portion of the sleeve 16 are open to allow proper operation of the movable jaw and that movement of the movable jaw shank 14 in a forward direction is limited by engagement of a lug 23 with the rear tooth 12 upon the shank 10 while rearward movement of the shank 14 is limited by engagement of the rear end of this shank and the lug 23 with the forward edge of the transverse wall 20.

The bracket 16 carries the inwardly directed lugs 24 at its forward end for engagement in the grooved sides of the movable jaw shank 14 and said jaw shank carries the lugs 25 upon its opposite sides for engagement against the lugs 24 to prevent accidental removal of the shank 14 from the main portion of the sleeve 16 when the latter is swung upon the pin 18, as will be clearly apparent. The nobs or enlargements 26 are formed upon the inner face of the outer wall of the main portion of the sleeve 16 at the opposite ends thereof, to prevent binding of the outer edge of the shank 14 against the sleeve.

It will be apparent that this wrench may be readily adjusted and it will be understood that the transverse wall 20 is curved for engagement by the operator's thumb. It will also be understood that the sides of the sleeve slope downwardly from the rear end 110

of the transverse wall of the main portion to the transverse wall 20 of the extended portion.

When it is desired to adjust the wrench, 5 the wall 20 is depressed by the thumb of the hand grasping the handle or shank 10, thus raising the movable jaw shank 14 and disengaging the teeth 15 thereof from the teeth 12. The movable jaw 13 and its shank 10 10 may then be moved in either direction to the main portion of the bracket 16 to the proper position, it being understood that the lugs 24 engage the upper edge of the shank 14 and serve to raise said shank as 15 the bracket 16 swings or rocks upon the pivot pin 18. When the movable jaw 13 assumes the proper position, the transverse wall 20 is relieved of pressure and the leaf spring 22 serves to return the sleeve 16 to 20 normal position, thus locking the teeth 15 and 12 together and retaining the movable jaw 13 in adjustable position.

From the foregoing it will be apparent that I have provided a wrench of extremely 25 simple construction and operation and composed of the minimum number of parts. It will be evident, however, that minor changes in the details of construction may be made

within the scope of the appended claim without in the slightest degree departing 30 from the spirit of my invention.

What is claimed is:

A wrench comprising a handle having one end terminating in a fixed jaw and its inner edge provided with teeth adjacent said fixed 35 jaw, a locking sleeve pivoted on the handle and having its side walls extending rearwardly and connected by a bridge, a spring interposed between the bridge and the adjacent edge of the handle, a shank slidable in 40 the sleeve and provided with teeth on its inner edge adapted for coöperation with the teeth on the handle, a jaw on one end of the shank adapted for coöperation with the fixed jaw, and spaced projections on the inner side of the wall of the sleeve adjacent 45 the outer edge of the shank for decreasing the frictional engagement between the shank and sleeve.

In testimony whereof, I affix my signature, in presence of two witnesses.

THOMAS B. SOMERS.
